UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

DOFFING DEVICE FOR SPOOLERS.

1,425,053.

Specification of Letters Patent. Patented Aug. 8, 1922.

Application filed December 10, 1917. Serial No. 206,390.

To all whom it may concern:

Be it known that I, ALONZO E. RHOADES, a citizen of the United States, residing at Hopedale, county of Worcester, State of

5 Massachusetts, have invented an Improvement in Doffing Devices for Spoolers, of which the following description, in connection with the accompanying drawing, is a specification, like characters on the drawing representing like parts.

This invention relates to spoolers and the object of the invention is to provide a simple and efficient means for doffing the yarn carrier.

15 The invention is particularly applicable to a type of spooler provided with yarn guiding and tension devices or other adjuncts so located as to render it more or less difficult for the operative to doff the 20 yarn carrier directly by hand and the object of the invention is therefore further to provide a doffing mechanism extending into a position readily accessible to the operative.

25 The object of the invention is further to provide a doffing mechanism for a spooler which shall not only lift the yarn carrier from its position on the holding support but shall also automatically shove the yarn 30 carrier laterally so that it may be delivered free of the holding support and, for example, onto the usual traveling endless conveyor of the spooler.

These and other objects and features of 35 the invention will appear more fully from the accompanying description and drawings and will be particularly pointed out in the claims.

The invention in a preferred form is 40 shown for convenience of illustration and disclosure in connection with a well known type of spooler provided with bobbin holders and guiding and tension mechanism of the type disclosed in the patent to Rhoades 45 No. 1,297,495, granted March 18, 1919.

In the drawings,

Figure 1 is a transverse sectional view of a portion of the type of spooler referred to sufficient to disclose the present invention 50 together with a preferred form of the present invention embodied therein;

Fig. 2 is a side elevation on a larger

scale of the bobbin holder and connected mechanism shown in Fig. 1;

Fig. 3 is a front elevation of the construction shown in Fig. 2;

Fig. 4 is a view similar to Fig. 3 showing the parts in the position occupied at the end of the doffing operation;

Fig. 5 is a view in cross section taken 60 on the line A—A of Fig. 3.

Fig. 6 is a detail view illustrating a plurality of spools and yarn carriers having doffing mechanism embodying my invention.

The present invention is not concerned 65 with the particular construction of the spooler and it is unnecessary therefore to describe in detail an ordinary type of spooler such as that herein illustrated. It will be sufficient to note that the frame 1 of the 70 spooler is provided with the usual drum shaft 2 extending longitudinally of the machine and from which belts run to the whorls 3 for driving the spool carriers 4 on which are vertically mounted the spools 75

5. There are usually two rows of these spools arranged on opposite sides of the machine and driven from the drum shaft. In front of and below each row of spools extends a horizontal rod 6 supported on the 80 frame. Holders for the yarn carriers or bobbins are provided usually one for each spool and such a holder is herein shown at 7 as a casting recessed to embrace the rod 6 and rigidly secured thereto by a set screw 85

8. The yarn carrier or bobbin holder is mounted on the rod 6 usually at an inclination to the horizontal although its particular position in this respect may be varied as desired.

90 The holder 7 at the lower end is provided with the usual step 9 from which projects a short spindle or stud 10 over which is placed the yarn carrier which is herein shown as a bobbin 11.

95 The yarn runs from the bobbin which is herein shown as of the filling wind type off from the end to guiding and tension devices 12, 13 and 14 carried at the upper end of the holder 7 and partly on a bracket 15 100 projecting over and above the step 9. These guiding and tension devices are herein illustrated as of the construction shown in the before-mentioned patent but may be of any

suitable type and construction. From the guiding and tension devices the yarn 11 runs to the usual traversing guide 16 of which there is one for each spool. These 5 traversing guides are carried by the usual horizontal traverse rod 17 which by suitable mechanism is given a vertical traversing movement over the length of the spools 5.

At the front of the frame 1 and beneath 10 the holders 7 and supported by the brackets 18 are mounted the usual boxes 19 to receive and hold the full yarn carriers while between these boxes and the frame is mounted an endless traveling conveyor 20 running 15 across the front of the frame and which receives upon its upper run the spent yarn carriers and carries them away to the end of the frame where they fall in suitable cans or containers.

20 The construction of spooler as above set forth is all well known and familiar and largely disclosed in the before mentioned patent.

In order to doff the yarn carriers such as 25 the bobbins 11 from the studs 10 it will be necessary for the operative to reach in over the box 19 between the holders 7 and beneath the brackets 18 with the supported guiding and tension devices. As these parts are 30 closely crowded together this becomes a somewhat difficult operation and delays the operation of the machine.

This invention provides means readily accessible to the hand of the operative by 35 which by a simple manual operation each yarn carrier is doffed and also at the end of the doffing operation is shoved laterally or ejected directly onto the upper run of the conveyor 20.

40 In the construction illustrated an operating device shown as a rod 21 is mounted on the holder adjacent the stud 10 and extended into a position to be readily accessible to the operative. This rod at its upper 45 end slides through a laterally projecting portion 22 of the bracket 18 and at its upper end is provided with a head or handle 23 easily within reach of the operative. At its lower end the rod is formed with a flattened portion 24 containing a slot 25 extending in a direction inclined to the length of the rod and this slotted portion rides over a pin 26 50 projecting from a lateral extension 27 of the step 9.

55 The rod 21 has mounted thereon and extending laterally therefrom a bifurcated arm 28. This arm 28 is secured to the rod by a hub 29 formed integrally therewith surrounding the rod and a set screw 30 passing through the hub into engagement with the rod.

60 When the rod is in its lowermost position the bifurcated arm 28 extends laterally beneath the yarn carrier or bobbin 11 as the bobbin is seated in its operative position

on the stud 10 and the bifurcations of the arm 28 pass at each side of the stud. The parts are then in the position shown in Fig. 3 of the drawing.

A spring-actuated cooperating mechanism or means for engaging the bobbin is herein shown as a plunger 31 mounted in the hub 29 of the arm 28 in line with the axis of the bobbin. This plunger is limited in its projecting movement by the cotter pin 70 32. A helical spring 33 is seated in the hub 29 surrounding the plunger shank and abuts between a recessed portion of the hub and the head of the plunger. When the parts are in the position shown in Fig. 3 and the 75 bobbin is on its stud the plunger is so arranged as to just about contact with the butt of the yarn carrier or the rings 34 usually surrounding the butt.

In the operation of the device when it is 80 desired to doff a bobbin the operative seizes the head 23 which is easily accessible and elevates the rod 21. This causes the bifurcated arm 28 resting beneath the bobbin to lift the bobbin off from and clear of the 85 stud 10. But owing to the inclination of the slot 25 riding over the pin 26 which makes a sliding cam connection between the rod and the holder and the fact that the plunger 31 rests against the butt of the bobbin it will 90 be seen that during this elevating movement the plunger is pressed inwardly compressing the spring 33. Hence when the bobbin reaches the end of its elevating movement and is freed from the stud 10 the plunger will spring outwardly and shove or force the bobbin laterally so as to throw it to one 95 side of the holder and consequently the bobbin will fall upon the upper run of the conveyor 20 and be carried away. Thus the 100 doffing operation is performed by a simple manual operation and in a manner which enables the operative to lose no time and in a manner which insures the ejection of the bobbin onto the end of the conveyor.

Having fully described my invention, what I claim as new and desire to secure by Letters Patent is:

1. In a spooler a yarn carrier holder, a stud carried thereby to receive and hold the yarn carrier in spooling position, an operating device mounted on the holder adjacent said stud and extended into a position to be readily accessible to the operative, an arm 115 extending from said device beneath the yarn carrier when seated on said stud, a sliding cam connection between said device and said holder, and a spring controlled laterally movable plunger carried by the rod adjacent the butt of the yarn carrier, the said 120 cam connection acting to compress the spring as the device is operated to doff the yarn carrier from said stud, whereby when the yarn carrier is lifted clear of the stud the plunger acts to shove it laterally. 125 130

2. In a spooler a yarn carrier holder, a stud carried thereby to receive and hold the yarn carrier in spooling position, an operating device mounted on the holder adjacent 5 said stud and extended into a position to be readily accessible to the operative, an arm extending from said device beneath the yarn carrier when seated on said stud, an inclined slot and pin connection between said device and said holder, and a spring-pressed laterally movable plunger carried by said device and engaging the butt of the yarn carrier when in spooling position on said stud, whereby, when said device is elevated to doff 10 the yarn carrier, the spring is compressed and being released when the yarn carrier is lifted clear of the stud the plunger acts to shove the yarn carrier laterally.
3. In a spooler a yarn carrier holder, 20 means mounted thereon to receive and hold the yarn carrier in spooling position, means mounted in fixed position with respect to the yarn carrier holder and acting when operated to withdraw the yarn carrier from said 25 holding means, and cooperating mechanism placed in operative condition by such withdrawing operation to then automatically shove the yarn carrier laterally whereby the yarn carrier is doffed from the holder.
4. In a spooler a plurality of studs to receive and hold the yarn carriers in spooling 30 position and a corresponding plurality of

separate individually manually operated means acting when operated to doff each 35 yarn carrier clear of its stud.

5. In a spooler a yarn carrier holder a stud on the holder to receive and hold the yarn carrier in spooling position, a device operated by a single manual movement, including means mounted on the holder adjacent 40 the stud and acting upon the operation of said device to lift the yarn carrier clear of said stud and shove it bodily laterally when clear of the stud.

6. In a spooler a stud to receive and hold 45 the yarn carrier in spooling position, an arm extending beneath the yarn carrier, means for elevating said arm to doff the yarn carrier from said stud, and means acting automatically to shove the bobbin laterally when 50 it is elevated clear of said stud.

7. In a spooler a stud to receive and hold 55 the yarn carrier in spooling position, an arm extending beneath the yarn carrier, means for elevating said arm to doff the yarn carrier from said stud, and spring-actuated means compressed during said elevating movement and released to shove the yarn carrier laterally when it is elevated clear of said stud.

In testimony whereof, I have signed my name to this specification.

ALONZO E. RHOADES.
